UNITED STATES PATENT OFFICE.

WILLIAM ERASTUS WILLIAMS, OF WILMETTE, ILLINOIS.

METAL SHEET USED FOR FREIGHT CAR STRUCTURES.

Application filed October 17, 1923. Serial No. 669,081.

My metal sheet relates specifically to steel ends for box cars but may be applied for other purposes.

In a steel end for a box car it is desirable to press the whole end from a single unitary sheet of steel, but it is difficult and expensive to roll a sheet of this size sufficiently thin for the purpose required. I seek to save this expense by my invention.

Reference will be had to the accompanying drawings in which Fig. 1 is a front elevation of my sheet of metal. Fig. 2 is a side sectional view and these two views are on somewhat smaller relative scale than the other figures in the case. Fig. 3 is an end elevation of the box car end. Fig. 4 is a transverse sectional view of a part of an end through a horizontal corrugation shown in Fig. 3 but on a somewhat larger scale. Fig. 5 is a horizontal transverse section through the corner and a vertical corrugation. Both Figs. 4 and 5 relate to the structure shown in Fig. 3. Fig. 6 is an end elevation of another form of a box car end and Fig. 7 is a vertical section through the end shown in Fig. 6.

Steel ends for box cars are usually made out of pieces riveted together. Some ends are made of two pieces some of three and others four or more and these pieces usually extend crosswise on the car and are riveted together at the seams. The purpose of this is that the top portion of an end is not required to be as thick metal as the lower portion and it is a common practice to make the upper section thinner than the lower section and then after the ends are pressed to shape the sections are riveted together. The making of these ends in sections as above indicated permits a cheaper grade of steel to be used because sheets of narrower width are cheaper than those of wider width as relates to widths that are needed for car ends. The pressing is then done in the separate sheets and after the sheets are pressed the sections are riveted together into the one sheet as has been the usual practice in the greater part of the steel ends heretofore used.

The labor involved in pressing the smaller sheets is substantially as great as any involved in pressing an entire sheet to form an entire end, the difference being only that in one case a little larger press is required. However, presses large enough to press the entire end are in common use and if the

metal might be had as cheaply for the one sheet end, the ends would all be made out of one sheet bodies.

Since the several pieces of the end where ends are made in section are riveted together it would be impractical to heat and press a sheet that had been riveted prior to the pressing for then the rivets would be distorted and the joint be weakened and it would come apart and thus not make a practicable job.

As it is a desirable thing to have a varying thickness in the metal for different portions of the end this alone substantially makes it impracticable to roll a sheet of metal as large as this with a taper that would be required or with the difference in thickness required as I have described.

In order to arrive at the results desired I buy the steel in different thicknesses as required for the different portions of the end and then when these sheets are in the flat I assemble them together on a flat table and weld the seams into an integrally united sheet which is made of the right thickness of metal in any portion of the end.

In Figs. 1 and 2, 1 indicates the top portion of the sheet, 2 the middle portion and 3 the lower portion, each varying in thickness as desired and these portions are welded together at points 4 and 5 and when so welded they become a unitary piece of metal which may be handled in the furnace and in the press making a unitary end sheet, which saves the cost in handling and in pressing and also saves cost as relates to riveting.

An end structure shown by Figs. 3, 4, and 5 is made stiff in every direction by means of the cross ribs 6 and 7 stiffened at their intersections by bulbous portions 8 which have the result of making a unitary stiff end substantially without a continuously straight neutral axis in any direction. Were this end of Fig. 3 made in separate pieces and riveted together it would not be practicable to get as stiff an end in every direction as may be done by making it of a unitary sheet. It will readily be seen that the stiffening ribs which cross the lapped riveted portions could not reasonably be made as stiff or free from a neutral axis in this field as if it were made of a unitary sheet. In order to get the full benefit of this type of an end or any other type of an end which seeks to be free from a neutral axis or a line of low

bending moment as compared with the balance of the area may not be had by a sheet that is spliced but is necessarily made out of a unitary sheet of metal.

5 Figs. 6 and 7 show an end that has been largely used and most generally made of separate sections riveted together but as I have above described in pressing this end in several pieces the cost of the press work 10 and the cost of the riveting is very much reduced by the use of a unitary end sheet like I have shown composed of sections of different thickness integrally united in the flat.

15 Heretofore in making ends like Figs 6 and 7 or similar thereto the different upper and lower pieces out of which the ends were made were overlapped and riveted together and this overlapping consumed extra metal 20 which serves no useful purpose beyond connecting the pieces previously pressed.

Owing to the variations in the draw and shrinkage of narrow sheets pressed in the usual way, it is necessary to provide for 25 overlapping the sheets where joined to allow for these variations and it is therefore not practical to join these separately pressed sheets by butt welding.

I make a saving of the metal and the labor 30 as well and get a nice uniform junction of the different pieces which compose the structure before they are heated for pressing. The heating operations used for softening 35 the metal for pressing purposes also serves to anneal the welded portions which aids in the restoring a normal integral connection of the metal of the sheet.

The lines 9, 10, 11, and 12 in the figures 40 do not indicate the seam but only show the juncture of the different thickness of the metal which form the integral sheet that composes the end.

45 It is my purpose to manufacture these sheets of varying thickness and supply the different end makers with these sheets of steel adapted for the purpose as described, which may be used with any type of stiffening form for an end.

What I claim is:—

50 1. An integral metal sheet, rolled in sec-

tions and then integrally united in the flat, and then formed into a box car member, having stiffening portions pressed in the body of the metal of the sheet.

2. A box car end, rolled in sections in flat 55 form, integrally united in the flat form, and then heated and pressed with stiffening portions while hot.

3. The method of forming sheet metal 60 ends for railway cars which consists in welding separately rolled metal sheets at their margins to form a single blank, then heating and pressing said blank to form a car end.

4. A railway car end made of a plurality 65 of metal sheets integrally united by welding at their margins, heated to an annealing temperature and then pressed into the desired shape.

5. A process of forming a railway car end 70 which consists of welding at their abutting margins a plurality of metal sheets of progressively varying thicknesses, heating the blank thus formed to an annealing temperature, and pressing said blank into a desired 75 shape.

6. A process of forming a railway car end which consists of welding at their abutting margins a plurality of sections of rolled 80 metal, heating the compound sheet and pressing the same to form a unitary end having integral stiffening portions.

7. A railway car end formed of a plurality 85 of metal sheets united by welding at their margins and having stiffening corrugations crossing said welded joints.

8. A railway car end formed from a sheet 90 of progressively varying thickness pressed to form a unitary end having integral stiffening portions.

9. A railway car end formed from a sheet 95 of metal thinnest at the top and increased in thickness abruptly and progressively toward the bottom and pressed to form a unitary end having integral stiffening portions.

Signed at Chicago, in the county of Cook and State of Illinois, this 11th day of October, 1923.

WILLIAM ERASTUS WILLIAMS.
